UNITED STATES PATENT OFFICE.

JOHN BALTHASAR AND ANGELO VIOLA, OF JERSEY CITY, NEW JERSEY.

AIR SUPPLY AND AUTOMATIC CONTROL FOR FURNACE DOORS.

Application filed June 19, 1924. Serial No. 720,971.

To all whom it may concern:

Be it known that we, JOHN BALTHASAR and ANGELO VIOLA, subjects of the King of Italy, residing at Jersey City, in the county 5 of Hudson and State of New Jersey, have invented certain new and useful Improvements in Air Supply and Automatic Controls for Furnace Doors, of which the following is a specification.

10 This invention relates to new and useful improvements in air supply and automatic control for furnace doors.

An important object of the invention is 15 to provide means for feeding air from a furnace door frame for the purpose of preventing the escape of heat, backfire, and gases from the furnace when the door is opened.

A further object of the invention is to 20 provide a control for the supply of air which will be rendered active when the door is opened for automatically causing the discharge of air and which will operate for cutting off the supply of air when the door 25 is closed.

Other objects and advantages of the invention will be apparent during the course of the following description.

In the accompanying drawings forming a 30 part of this specification and in which like numerals are employed for designating like parts throughout the same,

Figure 1 is a front elevational view of a furnace showing the fire box doors with the 35 air supply means embodying this invention properly associated therewith,

Figure 2 is a vertical sectional view through one fire-box door and the door frame associated therewith and further illustrates 40 the openings through which the air is discharged into the fire-box,

Figure 3 is a front elevational view of a door frame with the automatic air control 45 embodying this invention properly associated with the door carried by said frame,

Figure 4 is a top plan view, partly in section of the structure illustrated in Fig. 3,

Figure 5 is a detail plan view of the valves 50 employed for controlling the discharge of air,

Figure 6 is a fragmentary end elevational view of one of the valves illustrated in Fig. 5 and shows a portion of the automatic valve operating mechanism, the said valve being in 55 its opened position, and

Figure 7 is a similar view to Fig. 6 and shows the valve in its closed position.

In the drawings, wherein for the purpose of illustration is shown a preferred embodiment of this invention, the numeral 5 designates the front of a furnace which is provided with fire-box doors 6 associated with the door frames 7.

In Fig. 2, there is shown a sectional view of the door frame 7 for the purpose of illustrating the provision of a tubular passageway 8 which is formed therein. This passageway extends entirely around the frame 7 and is provided with a plurality of discharge orifices 9 which are formed in the frame 7 and extend at substantially a 45° angle from the inner face 7a of the frame 7. It is to be understood that the provision of these orifices 9 in all four sides of the frame 7 will form four converging walls of air, 75 illustrated by the arrow lines, which will meet at a point spaced inwardly from the frame 7.

In Fig. 1 there is illustrated an air supply pipe 10 having a T-joint 11 connected to its lower end for the purpose of delivering the supply of air to the branch pipes 12. The outer ends of these branch pipes 12 are provided with three-way connectors 13 having the angle pipes 14 connected thereto which are provided for delivering air to opposite sides of the door frames 7, the said angular pipes 14 being threaded, as at 14a in the frame 7. The branch pipes 12, in the form illustrated in Fig. 1, are provided with globe valves 15 by means of which the supply of air may be controlled manually.

In Figs. 2 to 7 inclusive there is shown a modified form of control for the air supply which includes the rotatable, tapered plug valves 16, illustrated in detail in Fig. 5, having transversely extending ports 17. These valves 16 are provided with squared inner ends 18 which are received within the sockets 19, formed on the opposite ends of the rod 20, and are secured therein by pins 21 there being universal joints 20a formed in the rod 20, as shown. These valves 16 are received within bosses 22 which are formed on the door frame 7 and which have pockets within which the lower ends of the angle pipes 14 are received. A restricted passageway 22a is formed in each boss 22 for providing a communication between the 110

end of the pipe 14 and the valve seat. It will be seen, by inspecting Fig. 2, that these valves 16, with their ports 17, may be arranged for controlling the flow of air from the pipes 14 into the tubular passageway 8 formed in the door frame 7. It will be understood that the valves 16, due to the restricted passageways 22, will necessarily have to partially rotate toward their opened positions before any communication will be established between the pipes 14 and the tubular passageway 8 formed in the frame 7.

In Figs. 3 and 4, the door 6 is illustrated as being swingingly connected to the door frame 7 by means of the pintles 23 which pass through the lugs 24 on the frame and the lugs 25 carried by the door 6. The valve 16 adjacent the door hinge is provided with a stem 26 having a squared, reduced end 27 to which is secured an arm 28, best illustrated in Figs. 4, 6 and 7. The outer end of this arm 28 is pivotally connected to a link 29 which has an enlarged, rectangular head 30 at its outer end. This head 30 is cut-away, as at 31 for the reception of the spaced rollers 32. Rigidly secured to the upper lug 25, carried by the furnace door 6, is a vertically extending post 33 which has secured to its upper end a spiral track 34 which is provided with a truly, horizontally extending portion 35 adjacent the end which is connected to the post 33. It will be seen, by inspecting Figs. 3 and 4 that this spiral track slopes downwardly from this horizontal portion 35 and terminates in an upturned end 36. It will, also, be seen by inspecting Fig. 4 that this track is of substantially elongated shape in plan view. In Figs. 3, 4, 6 and 7, the rollers 32 are illustrated as being positioned upon opposite sides of the track 34 and that movement of the said track between the rollers 32 will cause the link 29 to be moved for permitting the head 30 to follow the inclination of the track 34.

The operation of this automatic valve control is as follows:

It is to be understood that when the fire-box door 6 is in its closed position, the rollers 32 carried by the head 30 will be positioned upon the spiral track 34 adjacent the upturned end 36, as best illustrated in Fig. 7. The locating of this head 30 at the outer end of the track 34, the lower end of said track, will cause the link 29 to be positioned with its lower end in vertical alinement with the stem 26 of the valve 16 and below such stem. This movement of the lower end of the link 29 will cause the arm 28 to move for rotating the valve 16. When the door 6 is moved toward its opened position, the spiral track 34 will be forced through the opening 31 of the head 30 and the arm 29 will be drawn, through an arcuate path, into the position illustrated in Fig. 6. This up-

ward movement of the link 29 will cause the arm 28 to move for rotating the valve 16 to aline the port 17 with the pipe 14. By the time the door has been swung half-way open, or when the door is extending at right angles to the frame 7, the rollers 32, carried by the head 30, will have reached the outer end of the horizontally extending portion 35 of the track 34, whereupon further movement of the door 6 toward its fully opened position will cause the rollers to travel along such horizontal portion 35 and the valves 16 will be retained in their opened position. It is to be understood that when the door 6 is moved into its closed position, the said valves will also be closed, the valves starting on their travel to their closed positions when the rollers 32 leave the horizontally extending portion 35 of the track 34.

For the purpose of operating the valves 16 manually, should the automatic operating structure become inoperative for any reason, the valve 16 farthest from the door hinge is provided with a squared stem 36 adapted to receive a handle whereby the valves may be operated independently of the movement of the door.

It is now believed that the construction and operation of this device will be understood from the above detail description and that no further explanation is deemed necessary.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, we claim:

1. The combination with a furnace fire-box door-frame having a passageway formed therein provided with a plurality of air discharge orifices, of means for supplying air to said passageway, a rotary valve for controlling the amount of air supplied, a door swingingly carried by said frame, a post carried by said door, a track having an inclined portion and a horizontally extending portion carried by said post, and means connected to said valve and adapted to travel on said track for causing the swinging movement of said door to rotate said valve, the inclined portion of the track causing the rotation of the valve and the horizontally extending portion permitting the door to be moved from its half opened to its fully opened position without further rotating the valve.

2. The combination with a fire-box door frame having a passageway formed therein provided with a plurality of air discharge orifices, of means for supplying air to said

passageway, a rotary valve for controlling the amount of air supplied, a door swingingly carried by said frame, a perpendicular post carried by said door at a point spaced 5 from its hinging axis, a track having an inclined portion and a horizontally extending portion carried by said post, a laterally projecting arm fastened to the valve, a link pivotally connected to the arm, and spaced 10 parallel rollers journaled in the free end of said link, said rollers being adapted to engage the upper and lower faces of said

track for causing the swinging movement of said door to rotate said valve, the inclined portion of the track causing the rotation of 15 the valve and the horizontal portion permitting the door to be moved from its half-opened to its fully opened position without further rotating the valve.

In testimony whereof we affix our signatures.

JOHN BALTHASAR.
ANGELO VIOLA.
